UNITED STATES PATENT OFFICE.

FOLKERT FOLKERS, OF CRICHTON, ALABAMA, ASSIGNOR TO HIMSELF AND LESLIE E. CAMPBELL, OF MOBILE, ALABAMA.

AUTOMATIC LUBRICATOR.

1,271,305.

Specification of Letters Patent.

Patented July 2, 1918.

Application filed October 2, 1917. Serial No. 194,303.

To all whom it may concern:

Be it known that I, FOLKERT FOLKERS, a citizen of the United States, residing at Crichton, in the county of Mobile, State of Alabama, have invented certain new and useful Improvements in Automatic Lubricators, of which the following is a description, reference being had to the accompanying drawings, forming a part hereof.

10 My invention relates to lubricating devices and has for its object to provide a lubricating device particularly adapted for lubricating the guideways for elevators which will be adapted to be operated to supply 15 lubricant to such guideways by the movement of the elevator in stopping and starting.

With these and other objects hereinafter explained in view, my invention consists in 20 the construction and combination of elements hereinafter described and particularly pointed out in the claims.

Referring to the drawings.—

Figure 1 is an elevation of an elevator car 25 and a portion of its guide ways showing the lubricating device of my invention applied to the elevator car.

Fig. 2 is a vertical sectional view on an enlarged scale of the lubricating device, and 30 Fig. 3 is a top plan view of the same.

In the drawings, 1 indicates the elevator car having shoes 2, which travel on guideways 3 as the elevator car moves up and down. In order to make the elevator car 35 travel easily it is necessary to supply lubricant to these shoes at frequent intervals but in small quantity so as to avoid waste. The device of my invention is particularly adapted and intended for this purpose. The device 40 consists of an oil reservoir 4, preferably of glass, having an opening in its bottom controlled by a needle valve 5, the opening leading to a tube 6, preferably also of glass, inclosed in an outer tube 7, which supports 45 the reservoir 4 and has an opening 8 in it through which the oil as it passes down the tube 6 may be seen. This tube 7 is screw-threaded at its lower end into the top 9 of a receptacle which is suitably secured to the 50 elevator car and has its lower end 11 tapered to a suitable size and extended laterally into a suitable opening in the shoe 2. This receptacle 10 is preferably partly filled with waste or other absorbent material 12. When 55 the valve 5 is lifted a small quantity of oil

will flow down through tube 6 into receptacle 10 and will gradually filter through the waste 12 and be led through the end 11 to the shoe to the surface in contact with the way 3.

The valve 5 is carried by a valve rod 13 which near its upper end is reduced in diameter to form a shoulder 14 against which a coiled spring 15 bears to hold the valve to its seat. The valve rod is preferably inclosed in a vertical tube 16 having an opening 17 near its lower end to permit the oil to reach the opening controlled by the valve. At its upper end the tube 16 is screw threaded to receive a cap 18 through which the valve rod passes and which forms an abutment for the upper end of the spring 15.

To the upper end of the valve rod is pivoted an arm 20 which extends through an opening 21 in a vertical arm 22 carried by a plate 24 which is arranged to be capable of rotation on the vertical tube 16 on the top of the reservoir and serving as a cover for the filling opening 25. This arm 20 carries a weight 23 near its outer end, preferably made adjustable on the arm. The arm 20 is 80 made of spring metal so as to be resilient while acting also as a lever fulcrumed in the opening 21.

As the elevator car stops and starts in its movement from the ground to the upper floor of a building the lever arm 20 will, by reason of the inertia of the weight in starting or the momentum of the weight as the car is brought to a stop at a landing or otherwise, cause the valve rod to be lifted and permit a small amount of oil to escape into tube 6 and into receptacle 10, thus supplying oil as it is needed to lubricate the guideways. By adjusting weight 23 on the arm 20, the movement of the valve rod and the consequent feed of oil may be regulated.

It will, of course, be understood that I do not desire to be limited to the precise construction shown or to the use of the invention in connection with elevators, as it is obvious that it may be used whenever an element moves vertically on a guideway and is subject to starting and stopping.

Having thus described my invention, what I claim is:

1. A lubricating device for an element movable on vertical ways, adapted to be carried on the movable element, comprising an oil reservoir, a valve controlling the flow of oil from the reservoir, a valve rod for the

valve, a spring lever pivoted at one end to the valve rod, a fulcrum for the spring lever carried by the reservoir, a weight adjustable on the spring lever, and a spring for holding 5 the valve normally closed.

2. A lubricating device for an element movable on vertical ways, adapted to be carried on the movable element, comprising an oil reservoir, a valve controlling the flow of 10 oil from the reservoir, a valve rod for the valve, a spring lever pivoted at one end to the valve rod, a fulcrum for the spring lever carried by the reservoir, a weight adjustable on the spring lever, and a spring carried by 15 the valve rod for holding the valve normally closed.

3. A lubricating device for an element

movable on vertical ways adapted to be carried on the movable element, comprising an oil reservoir, having a filling opening in its 20 top, a valve controlling the flow of oil from the reservoir, a valve rod for the valve, a plate mounted to rotate on the reservoir adapted to serve as a cover for the filling opening and provided with a vertical arm, a 25 spring arm fulcrumed in said vertical arm connected with the valve rod at one end and carrying a weight near its free end, and a spring arranged to hold the valve normally closed.

In testimony whereof I affix my signature this 28th day of September 1917.

FOLKERT FOLKERS.
